UNITED STATES PATENT OFFICE

CLARENCE B. HARBISON, OF LIMA, OHIO, ASSIGNOR TO THE OHIO STEEL FOUNDRY COMPANY, OF LIMA, OHIO, A CORPORATION OF OHIO

TENDER-FRAME STRUCTURE

Application filed July 25, 1927. Serial No. 208,141.

This invention relates to improvements in locomotive tenders, and has for its principal object to produce a new and improved construction and method of manufacturing the same, in which the lower portion of the tank body is formed of an integral skeleton frame casting of sufficient strength to provide in effect a main frame structure with interior baffle plates, the open portions of said casting being thereafter finished by welding in relatively thin metal sheets to complete the bottom walls of the tank.

The invention may best be understood by reference to the accompanying drawings, in which

Figure 1 is a fragmentary side view of a finished tender body constructed in accordance with my invention, with the upper parts of the body broken away,

Figure 2 is a transverse section taken on line 2—2 of Figure 1, and indicating the completed tank body above the base casting,

Figures 3 and 4 are half-plan views of the rear and front ends respectively, of the main frame casting, showing the open framework of the casting before the bottom walls are welded in place therein,

Figures 5, 6 and 7 are sectional views taken on lines 5—5, 6—6 and 7—7 respectively, of Figure 4, showing the bottom walls welded in place.

Referring now to details showing in the drawings, the invention consists in providing a base casting 10 adapted to form the main frame of a tender, and having, when completed, the upright end and side walls 11 and 12 of the tank body attached thereto, so that the base casting also forms a part of the bottom of said tank. In forming the casting 10 a skeleton framework having sufficient strength and rigidity is provided, and the open portions of said frame are thereafter closed by relatively lighter sheets of steel which are welded in place to complete the bottom of the tank. Details of the base frame structure and welded-in sections will now be described.

The main casting 10 is best shown in Figures 3 and 4 before the welded-in sections are applied. In these figures a hollow beam

member 20 extends longitudinally of the center of the frame with suitable end sills 21 and 22 and bolster supports 17, 17, said beam member is preferably box-like in cross section, having side walls, 23, 23, upper wall 24 and lower wall 25, as is best shown in the sections of Figures 2, 5, 6 and 7. In the form shown the center beam is widened at the forward end to conform with the shape of the coal compartment which is defined by the upright inner walls 18, 18 (Figure 5) which connect with the main frame casting along lines 19, 19, shown in Figure 4.

A plurality of transverse beams are provided, including box section beam 27 at the rear bolster support 17 and another beam 28 at the front bolster support of the tender. Other transverse members, such as upright ribs 29, 29 may also be provided. Diagonal braces 11^a, 11^a may be connected to the transverse members to support the side walls 12, 12 as shown. In the form shown, the transverse members 27, 28 and 29 form baffle plates to restrain excessive movement of the water in the tank, and may also be provided with apertures, as for instance, aperture 29^a near the bottom of the tank, to permit passage of water between adjacent tank sections.

The outer margin of the base casting consists of side members 30, 30, each herein consisting of a vertical member with a rounded inturned flange 31.

As seen in Figures 3 and 4, the base casting is formed with openings 35, 35 between the center beam 20, side members 30, 30 and transverse members 27, 28 and 29. The marginal portions of the frame about these openings are preferably provided with horizontally disposed flanges 36, 36 which are countersunk slightly, as shown in Figures 2, 3 and 4, to receive flat steel plates 37, 37 in fitting engagement therein. These plates are secured in place by water-tight joints, preferably by welding, as indicated in Figures 5, 6 and 7, and thus form the bottom of the tank. Any other openings, such as core holes, etc., formed in the casting may be closed in a similar manner, so that said casting forms an integral part of the tank as well as the main frame of the tender, with its bolster support 17, 17

resting directly on the truck bolsters. This structure also eliminates the necessity for side sills, the side members 30, 30 providing sufficient strength to support the sides of the tank.

5 Although I have shown and described certain embodiments of my invention, it will be understood that I do not wish to be limited to the exact construction illustrated and described, but that various changes and modifications may be made without departing from the spirit and scope of the invention.

I claim:

- 15 1. In a tender, an integral cast main frame including longitudinal and transverse frame members having openings therebetween, upright walls connected to said members to form the sides of the tender tank, horizontally disposed flanged members surrounding said openings countersunk adjacent their margins, and sheet metal pieces fitting in said countersunk flanges and welded thereto to form with said main frame casting the bottom of said tank.
- 20 2. In a tender, an integral cast main frame including longitudinal and transverse frame members having openings therebetween, upright walls connected to said members to form the sides of the tender tank, and sheet metal pieces extending across the openings in said casting adjacent the bottom thereof to form with the latter the bottom of said tank, said longitudinal and transverse members forming upright baffles in said tank.
- 25 3. In a tender, an integral cast main frame including longitudinal and transverse frame members having openings therebetween, upright walls connected to said members to form the sides of the tender tank, and sheet metal pieces extending across the openings in said casting adjacent the bottom thereof to form with the latter the bottom of said tank, said longitudinal and transverse members forming upright baffles in said tank and having apertures adjacent the bottom of the tank communicating between adjacent sides of said baffles.

Signed at Chicago, Ill., this 12th day of July, 1927.

50 CLARENCE B. HARBISON.
